The ornamental design for a carrier for mounting on all terrain vehicles, as shown and described.

DESCRIPTION

FIG. 1 is a perspective view of a carrier for mounting on all terrain vehicles showing my new design;

FIG. 2 is a front elevational view thereof;

FIG. 3 is a top plan view;

FIG. 4 is an end elevational view showing the end opposite to that shown in FIG. 1;

FIG. 5 is a rear elevational view; and,

FIG. 6 is a bottom plan view.

Fig. 5.

*Fig. 6.**Fig. 3.**Fig. 2.*
